UNITED STATES PATENT OFFICE.

AUGIE L. HANSEN, OF CHICAGO, ILLINOIS, ASSIGNOR TO A. L. HANSEN MFG. CO., OF CHICAGO, ILLINOIS, A CORPORATION OF ILLINOIS.

DOOR FASTENER.

Application filed June 14, 1926. Serial No. 115,864.

This invention relates to door fasteners, and more particularly for swinging doors such as are used at the rear of closed bodies for commercial vehicles.

5 In the present disclosure, the fastener is applied to a double door construction, in which the doors swing outwardly for access to the interior of the body or compartment. The object of the invention is to provide a secure 10 fastening for the doors at center, top and bottom and so operating as to draw the doors tightly together in a rattle-proof and weather-proof closure.

In the accompanying drawings,

15 Figure 1 is a rear view of a vehicle showing a typical installation on the doors.

Figure 2 is an enlarged detail view showing the casing of the fastening mechanism as it appears from the inside of the compartment.

20 Figure 3 is a view in horizontal section through the fastener as taken on line 3—3 of Figure 2.

Figure 4 is a view in cross-section taken on line 4—4 of Figure 3.

Figure 5 is a detail view in sections taken on line 5—5 of Figure 4, showing the spring finger acting on the bolt plate; and

25 Figure 6 is a perspective view of the operating handle and arms for padlock.

As shown in Figure 1, the body or compartment A of a closed vehicle for commercial purpose, is of the usual frame construction, and provided with a rear opening closed by 30 two doors B—B which are hinged to opposite sides of the door frame, and swing together in substantial abutting contact at their edges. As is usual in door construction, the top and bottom rails a are recessed so that the doors 35 close flush therewith, and one door (on the right, Figure 1) has a marginal strip b which overlaps the edge of the opposite door when the two are closed.

The fastener consists in general of a primary fastening member mounted on the doors 45 midway between the top and bottom thereof, and auxiliary fastening members in the form of endwise movable rods engaging the top and bottom rails of the door frame, the entire device being operated by a handle from the outside of the compartment.

The primary locking member comprises a circular lock casing 1, divided into two sections 1^a and 1^b along a line coinciding with the 50 adjacent edges of the doors. The main sec-

tion 1^a, which is somewhat greater than a semi-circle, forms the bolt casing and is mounted on the right-hand door, as shown in Figure 1. The smaller section 1^b is mounted on the opposite door and serves as the keeper 60 for a rotative bolt or plate within the bolt casing.

The bolt casing is made up of a circular base plate 2 and a dished or recessed cover 3 having a marginal flange 3^a which is riveted 65 to the plate 2. Both the plate and cover are divided into sectors, as already described, each sector being secured to the opposite door by bolts 4.

Within the bolt casing 1^a is the bolt plate 70 5 consisting of a sector of a circle of substantially the same contour as the casing section. This plate is mounted on a square bushing 6, having a square bore therethrough, said bushing being journaled at the geometric 75 center of the bolt casing and having an extension passing through a hole bored in the door to the outside thereof. Into the bushing is inserted the square shank 7^a of a T-handle 7. About the periphery of the bolt 80 plate 5 is a flange 5^a, said plate lying close to the base plate 2 of its casing and the flange extending at right angles toward the cover 3, as shown in Figure 3.

The forward end of the flange 5^a is beveled 85 on its inner face to form a cam surface 5^b.

The bolt plate is rotated in a clockwise direction through an arc of 90° from a position in which its straight line edge is vertical and flush with the opening along the 90 edge of its casing, to a position in which the same edge is horizontal. These positions of the plate are also determined by the T-handle 7 (Figure 6), which stands vertical and horizontal in corresponding positions of the bolt 95 plate.

In order to restrain the movement of the plate, a spring finger 8 is mounted within the casing section 1^a and extending obliquely to the radius thereof. This spring finger is 100 riveted at its inner end, and provided at its outer end with a depressed lug 8^a. At points along the edge of the flange 5^a are formed notches 9, 9, spaced 90° apart, and corresponding to the extreme positions of the bolt 105 plate, as shown in Figure 5. In this manner the spring finger exerts a yielding pressure on the plate in its movement, and also engages the two notches 9, 9, at each end of its movement in both directions, thus making it neces- 110

sary to apply a slight turning pressure to release the plate from either position.

The smaller section 1^b of the casing has already been identified as the keeper, and in-
5 to which the bolt plate is rotated to effect the fastening of the doors. The plate engaging member of the keeper is a roller 10, jour-
nalled on the outer wall or cover plate 3 of the casing section, by means of a journal pin
10 10^a. The roller however clears the inner wall
2, so that the plate 5, passes between the end of the roller and the adjacent surface of the keeper casing. The location of the roller is such that its periphery lies in the path of the
15 inner face of the flange 5^a of the plate, so that as the plate is rotated into locking position, the cam surface 5^a at the forward end of the flange rides onto the roller, thereby drawing the doors together and prevents them from
20 rattling or sagging, and otherwise providing a tight joint between the edges of the doors.

In addition to the primary fastening member, are secondary or auxiliary closing members in the form of rods 11, 11, extending up-
25 wardly and downwardly in vertical direc-
tions and adapted to project at their ends be-
yond the edges of the door frames. These rods are pivotally connected to the bolt plate
5, by means of journal pins 12, 12, fixed to the
30 plate on opposite sides of its center and 180° apart. These pins rotate with the plate through angles of 90°, or 45° above and below the horizontal. The pin 12 to the left of the center (Figure 2) rides in a curvilinear
35 slot 13 of 90° extent, formed in the cover plate 4 of the casing, whereas, the outer vertical edge of the cover plate is cut away as at 14, to permit the right hand pin to shift. The outer ends of the rods 11, are supported
40 in angle plates 15, fixed to the door near its top and bottom edges, these plates having an outwardly bent flange 15^a with a hole therein through which the rods slide. By preference, metal strike plates 16, are fixed to the door frame to contact with the end rods. In the drawings the upper rod 11 only, is shown complete, it being understood that the lower rod is a duplicate thereof.

Associated with the T-handle 7 on the
50 outside of the doors are two bars 17 and 18, the former being fixed in horizontal position to the door carrying the handle, by means of screws 17^a and preferably counter-sunk in the metal strip *b* along the edge of the door.
55 The other bar 18 is mounted on the square bushing 6 just inwardly from the stem 7^b of the handle and turns with it and in a plane adjacent the fixed bar 17. The free end of each bar is bent outwardly at right angles
60 and holes 19, 19 punched therein. The movable bar 18 is slightly shorter than the fixed bar so that the two end portions fit into each other when the same are parallel and the holes 19, 19 register with each other. Thus
65 assuming in Figure 7 that the T-handle

stands crosswise when the doors are fas-
tened, the two bars 17 and 18, are brought together and a padlock *c* inserted through the registering holes 19, 19, thus locking the handle against turning. The movable bar 70
18 preferably carries a plate 20, having an outstanding lip 20^a extending endwise from the outer end, the purpose of this lip being to prevent the padlock from marring the door as it would, if allowed to swing freely. 75

The details of the fastening device may manifestly be modified without departing from the spirit of the invention, and therefore I do not wish to be limited except in so far as the invention is specified in the ap- 80
85 pended claims.

I claim as my invention:

1. A door fastener comprising a relatively flat circular casing divided into sections adapted to be mounted on opposite sides of 85 the edge of a door in registering relation, a bolt plate journaled in one of said sections and consisting of the sector of a disc conforming to its section of the casing and having a concentric marginal flange, a handle 90 having a shank on which said bolt plate is mounted, a keeper mounted in the other section of said casing and adapted to be engaged by the inner face of said flange of said bolt plate, a rod pivotally connected at one 95 end with said bolt plate through the medium of a pin travelling in a slot in said casing, a rod terminating at its free end adjacent another edge of said door and adapted to be shifted endwise in the movement of said bolt 100 plate into and out of fastening position to simultaneously fasten and unfasten said door at said last mentioned edge.

2. A fastener for doors, comprising a circular casing divided into sections adapted to 105 be mounted on the inside of said doors, a ro-
tative bolt plate mounted in one of said sec-
tions, a keeper mounted in the other section,
a handle on the outside of one door and in-
cluding a shank connected with said bolt 110 plate, a bar fixed to said last mentioned door and extending radially from the axis of said handle, a bar carried by said handle and mov- 115
ing in a plane adjacent said fixed bar, said bars having holes in the ends thereof adapted to register in the fastening position of said bolt plate to receive a padlock, the outermost bars having a flange adjacent its holes and adapted to restrict the swinging movement of 120 said padlock.

3. A fastener for doors, comprising a cir-
cular casing divided into sections adapted 125 to be mounted on the inside of said doors, a ro-
tative bolt plate mounted in one of said sec-
tions, a keeper mounted in the other section,
a handle on the outside of one door and in-
cluding a shank connected with said bolt plate, a bar fixed to said last mentioned door and extending radially from the axis of said handle, a bar carried by said handle and mov- 130

- ing in a plane adjacent said fixed bar, said bars having their end portions bent at right angles and holes formed therein to receive a padlock when said bars are in registering relation, and a plate fixed to said movable bar adjacent the hole therein and having a lip extending outwardly at right angles into the path of the swinging movement of said padlock.
10. 4. A fastener for doors comprising a casing mounted adjacent one edge of a door, a bolt plate journalled in said casing and having a concentric marginal flange of a predetermined arcuate extent, a keeper adapted to 15 be engaged by the internal face of said flange, and a leaf spring fixed at one end to the inside of said casing and having a detent at its free end bearing against the edge of said flange, the latter having notches spaced apart 20 at a predetermined angle and coacting with said spring to hold said plate against rotation in its fastened and unfastened positions.
5. A fastener for doors comprising a casing divided into sections of unequal size 25 mounted in registering relation on opposite sides of the edge of a door, a bolt plate journalled in the larger section of said casing and at the geometric center thereof, a roller journalled in said smaller section of the casing and offset from the plane of said bolt plate, the latter having a concentric arcuate flange adapted to have rolling contact with said roller along its internal face in the rotation of said plate to and from fastening 30 position, and a leaf spring fixed at one end to the larger section and having a detent at its free end bearing against the edge of said flange, the latter having notches spaced apart at a predetermined angle and coacting 35 with said spring to hold said plate against rotation in its fastened and unfastened positions.
6. A door fastener comprising a relatively flat shallow circular casing consisting of 40 a base plate and a cover plate and divided into sections adapted to be secured on opposite sides of an edge of the door to be fastened, a bolt plate mounted in one of the sections and rotative about the geometric center of the casing, said plate having substan-
- tially the contour as its section and provided with a concentric marginal flange extending transversely of said casing at right angles, and a roller journalled in the other section and adapted for rolling contact with the internal face of said flange in the turning of said bolt plate into and out of fastening position, and means acting on said bolt plate for yieldingly holding the same in and out of fastening position.
7. A door fastener comprising a shallow circular casing consisting of a base plate and a cover plate and divided into larger and smaller sections, a bolt plate journalled at the geometric center of the casing and having substantially the same contour as the larger section thereof and provided with a concentric marginal flange extending transversely of said casing, and a roller mounted within said smaller section and offset from the bolt plate to engage the inner face of said flange, the forward edge of the latter being bevelled to permit of a drawing of the sections together as said flange and roller contact.
8. A fastener for doors comprising a relatively flat circular casing divided into sections adapted to be mounted on the inside of said doors in registering relation on the opposite edges thereof, a bolt plate journalled in one of said sections and consisting of the sector of a disc conforming to its section of the casing and having a concentric marginal flange, a handle on the outside of said door having a shank extending therethrough on which said bolt plate is mounted, a roller journalled in the other section of said casing and adapted to be engaged by the inner face of said flange of said bolt plate, a rod pivotally connected at one end with said bolt plate adjacent its center and adapted to be shifted endwise in the movement of said bolt plate to fasten and unfasten said door at an adjacent edge, and means for yieldingly holding said bolt plate in and out of door fastening position.

Signed at Chicago, Ill., this 9th day of June, 1926.

AUGIE L. HANSEN.
